APPARATUS FOR ASSEMBLING PLUGS IN PRIMER TUBES

William E. Walsh, Chicago, Ill.

Application August 2, 1954, Serial No. 447,370

3 Claims. (Cl. 209—72)

The present invention relates to a novel apparatus for forming and inserting diaphragms or plugs in tubular bodies, and more particularly to a novel apparatus which is especially useful for forming and inserting diaphragms in primer tubes of high explosive shells or bombs and the like.

As is well known, high explosive bombs or artillery shells are provided with a priming charge which may be easily ignited by a suitable detonator and which, in turn, serves to ignite the main charge. Such priming charges are usually placed in a long perforated tube. Such tubes are made in certain standard lengths, but it is often desirable to vary the amount of the priming charge in various tubes. The amount of the priming charge which may be inserted in any particular tube is determined by locating a diaphragm or plug at a predetermined position within the tube and then filling one end of the tube with the charge.

Before the present invention, it has been the practice to insert the diaphragm or plug in priming tubes by hand. This is a slow tedious hand operation so that the labor cost is unduly high. Furthermore, the plugs or diaphragms are held and secured in the desired position within the tube by means of a suitable lacquer or other adhesive material and it is difficult for the hand operators to locate the lacquer at the proper position within the primer tube for most effective holding of the plug or diaphragm.

It is an object of the present invention to provide a novel apparatus for inserting plugs or diaphragms to a predetermined position within tubular bodies such as primer tubes in a rapid and economical manner.

Another object of the present invention is to provide a novel apparatus for automatically inserting a plurality of plugs or diaphragms into a plurality of primer tubes in a substantially continuous manner.

A further object of the present invention is to provide a novel automatic apparatus for injecting a suitable lacquer or other adhesive material into a predetermined portion of a tubular body such as a primer tube and for subsequently locating a plug or diaphragm in said predetermined portion of the tube.

Still another object of the present invention is to provide a novel apparatus for automatically forming plugs or diaphragms from stock material and inserting the formed diaphragms into a tubular body.

A still further object of the present invention is to provide a novel apparatus for successively inserting a plurality of plugs or diaphragms into a plurality of tubular bodies such as primer tubes moving along a path of travel and for subsequently separating satisfactory tube and diaphragm assemblies from unsatisfactory assemblies. A more specific object of the present invention is to provide a novel apparatus for intermittently conveying a plurality of tubular bodies such as primer tubes to successive work stations, for performing various operations at said stations resulting in proper insertion and retention of a plug or diaphragm within a tube and for automatically operating the various elements of the apparatus in predetermined timed relationship to each other.

A still further object of the present invention is to provide an apparatus of the above described type which may be relatively economically manufactured and serviced and which is explosion-proof so that it may be used in ordnance plants.

Other objects and advantages of the present invention will become apparent from the following description and the accompanying drawings wherein:

Fig. 1 is a side elevational view of the apparatus of this invention with portions broken away and certain elements omitted for clearness;

Fig. 2 is a right-hand end view of the apparatus shown in Fig. 1;

Fig. 3 is a plan view of the apparatus in this invention;

Fig. 4 is an enlarged cross sectional view of a primer tube and diaphragm assembly fabricated by the apparatus of this invention and taken along line 4—4 in Fig. 5;

Fig. 5 is a perspective view of the primer tube and diaphragm assembly;

Fig. 6 is a plan view of the means for injecting lacquer or other suitable adhesive material into the primer tube at a first work station of the apparatus;

Fig. 7 is an elevational view of the means shown in Fig. 6;

Fig. 8 is a cross sectional view taken along line 8—8 in Fig. 7;

Fig. 9 is an enlarged fragmentary cross sectional view showing how lacquer or other suitable adhesive material is injected into a primer tube;

Fig. 10 is an elevational view of the means at a second work station of the apparatus, which means functions to form plugs or diaphragms and partially insert the diaphragms within the primer tubes;

Fig. 11 is a plan view of the apparatus shown in Fig. 10;

Fig. 12 is an enlarged fragmentary cross sectional view similar to Fig. 14 and showing how a diaphragm is inserted into the end of the primer tube;

Fig. 13 is a left-hand end view of the means shown in Fig. 10;

Fig. 14 is a cross sectional view taken along line 14—14 in Fig. 13;

Fig. 15 is a fragmentary cross sectional view taken along line 15—15 in Fig. 14;

Fig. 16 is a plan view of means at a third work station of the apparatus for positioning a previously inserted diaphragm to a predetermined depth within a primer tube;

Fig. 17 is an elevational view of the means shown in Fig. 16;

Fig. 18 is an enlarged fragmentary cross sectional view showing how the means of Figs. 16 and 17 operates to position a diaphragm within the primer tube;

Fig. 19 is a plan view of means at a fourth work station of the apparatus, which means functions to check or inspect the primer tube and diaphragm assembly to determine if the diaphragm is properly positioned;

Fig. 20 is an elevational view of the means shown in Fig. 19;

Fig. 21 is an enlarged fragmentary cross sectional view showing how the means of Figs. 19 and 20 functions to check a primer tube and diaphragm assembly; and

Fig. 22 is a diagrammatic view of the actuating end control means of the apparatus.

Referring now more specifically to the drawings wherein like parts are designated by the same numerals throughout the various figures, an apparatus 30 embodying the principles of this invention is shown in Figs. 1, 2 and 3 and includes conveyor means 32 for successively con-

veying a plurality of primer tubes 34 past work stations 36, 38, 40 and 42. Means 44 is located at the station 36 for ejecting lacquer or other suitable material into the primer tubes and means 46 is disposed at the station 38 for successively forming a plurality of plugs or diaphragms 48 and inserting the diaphragms into the ends of the tubes. At the station 40 there is located means 50 for positioning the previously inserted diaphragms to the proper position within the primer tubes and means 52 is located at the station 42 for checking to see whether or not diaphragms have been properly positioned within the tubes.

The primer tube and diaphragm assembly which is shown best in Figs. 4 and 5 forms no part of the present invention and needs not be described in detail. Therefore, it suffices to state that the primer tube 34 is usually in the form of an elongated metal tube having a plurality of perforations 54 and the diaphragm 48 is in the form of a cup shaped paper or other sheet material member. A lacquer or other suitable material 56 is located at the proper position within the primer tube for holding the diaphragm and sealing the peripheral junction between the diaphragm and the tube against the passage of the priming charge or powder, not shown, which is subsequently inserted into the tube through the tube end 58.

The conveying means 32 includes a shaft 60 suitably rotatably supported on a base or frame structure 62 of the apparatus and operatively connected with and adapted to be driven by a pneumatic motor 64 of known construction. A large gear 66 is fixed on one end portion of the shaft and a disk or turret wheel 68 is fixed adjacent the opposite end of the shaft. A plurality of rods 70 extend between and are connected to the gear and the disk. Another disk 72 is longitudinally adjustably mounted on the shaft 60 and the rods 70. Rim portions of the disks 68 and 72 are provided with a plurality of circumferentially spaced notches or pockets 74 and 76 which are adapted to receive and retain a primer tube extending between the disks. As will be understood, the conveyor means may be adapted for receiving primer tubes of various lengths by adjusting the disk 72 toward or away from the disk 68. If desired, the rim portions of the disks having the pockets therein may be formed so as to be removable so that the conveyor may be adapted to accommodate primer tubes having different diameters by substituting rim portions on the disks having pockets of different sizes. As shown in Fig. 2, a curved bar or rail 78 is suitably mounted on the apparatus frame for retaining primer tubes in the pockets of the disks while the tubes are being conveyed past the work stations. In addition, the outer ends of the pockets or notches 76 are closed by a plate member 80 shown best in Figs. 1 and 3 for preventing the primer tubes from moving toward the right as viewed in these figures while the tubes are conveyed past the work stations.

The primer tubes 34 are supplied to the conveyor from a hopper 82 which is shown in Figs. 1, 2 and 3. The hopper is provided with downwardly converging bottom sections 84 and 86 which direct the primer tubes between vertical guide members 88 and 90. In order to vibrate the hopper and the mass primer tubes disposed therein for facilitating passing of the primer tubes between the guide members, a plurality of eccentric cams 92 are mounted on a rotatable shaft 94 in position for intermittent engagement with the bottom section 86 of the hopper. The shaft 94 is continuously driven by means of an air motor 96 of known construction.

The guide members 88 and 90 direct the primer tubes to the peripheries of a pair of transfer disks 98 and 100 which are mounted on a rotatably supported shaft 102. As shown best in Fig. 2, the transfer disks are provided with a plurality of circumferentially spaced pockets 104 which, upon coming into alignment with the guide members 88 and 90, receive a primer tube. The transfer

disks are rotated in timed relationship with the disks of the conveyor means so that the primer tubes are carried by the transfer disks and disposed in the pockets of the conveyor disks. This timed movement of the two sets of disks is obtained by fixing a gear 106 on the shaft 102, which gear is driven by the large gear 66 of the conveyor means. In order to prevent the primer tubes from falling from the pockets of the transfer disks prematurely, retaining bars or rails 108 are suitably positioned.

The means 44 for injecting the lacquer or other suitable material into the primer tube at the work station 36 is shown best in Figs. 3 and 6 through 8. This means includes a flow gun 110 disposed for straight line reciprocating movement and having its discharge end connected with an elongated hollow tube 112 which has a nozzle tube 114 fixed on the free end thereof. Lacquer or any other suitable material is supplied to the flow gun from a tank 116 through a flexible conduit 118. The lacquer is forced to the gun under pressure and in order to accomplish this, the interior of the tank is connected to a suitable source of air pressure by means of an air line 120.

In order to reciprocate the flow gun and hollow tube to insert the nozzle 114 into and withdraw the nozzle from a properly positioned primer tube, the flow gun is connected to a double acting piston 122 which extends from an air cylinder 124. In addition, the outer end portion of the hollow tube 112 is suitably slidably supported in a bracket 126. Actuation of the piston is controlled by a double acting solenoid valve 128 which is connected with a source of air pressure by means of air lines 130 and 132. As will appear from the description hereinbelow, the solenoid valve is controlled by an electric circuit so that the piston is actuated in predetermined timed relationship with the conveyor means. This electric circuit includes a microswitch 134 which is actuated by a cam 136 fixed on and carried with the hollow tube 112. The purpose of this switch will be set forth fully hereinbelow. In addition, a microswitch 138 is provided and is actuated by a cam member 140 fixed on and carried by the hollow tube 112 and movable therewith to the broken line position shown in Fig. 6. The switch 138 controls the solenoid valve 128 so as to limit the forward stroke of the piston and thus, the depth which the nozzle 114 may enter the primer tube. It will be appreciated that the length of the piston stroke may be easily varied by adjusting the position of the cam member 140 on the hollow tube 112. In order to further support the flow gun and the hollow tube 112, a guide rod 142 is mounted parallel to the hollow tube 112 and the cam members 136 and 140 are provided with apertured extensions which are slidable on the guide rod.

It is desirable that the lacquer or other suitable material be injected into the primer tube substantially only at the position within the tube to which the diaphragm is to be finally located. Therefore, the flow gun is provided with trigger means 144 which, when actuated, is operable to permit the lacquer to be forced from the nozzle. A cam 146 is disposed for engaging and actuating the flow gun director shortly before the cam member 140 engages the microswitch 138. The cam 146 is mounted for adjustment longitudinally of the stroke of the flow gun so that it may be disposed to actuate the director when the nozzle 114 has reached any predetermined depth within the primer tube.

The means 46 for forming the diaphragms or plugs and for inserting the diaphragms into the ends of the primer tubes at the work station 38 is shown in Figs. 1, 3 and 10 through 15. This means includes a double acting air cylinder 150 which actuates a piston 152 slidably disposed therein. A suitable double acting solenoid valve 154 is provided for controlling the operation of the piston which valve is connected to a source of air under pressure by means of air lines 156 and 158. An elongated rod or plunger 160 is connected to and actuated by the

piston 152 and extends into a die structure 162. A microswitch 164 is disposed for engagement by a cam member 166 adjustably fixed on the rod 160 for controlling the solenoid 154 so as to limit the length of the piston stroke and a similar microswitch 168 actuated by a cam member 170 fixed on the rod 160 is provided for a purpose which will be set forth more fully below. The die structure 162 as shown best in Figs. 12 and 14 includes a fixed hollow body member 164. A sleeve 166 is slidably disposed within the body member and is provided with an apertured bushing 168 which slidably receives the plunger or rod 160. At the opposite end of the sleeve, there is a die member 170 having a central aperture 172 therethrough slidably receiving the end of the plunger 160. A die member 174 is suitably mounted to the body 164 by means of a plate 176 for cooperation with the die member 170 to cut diaphragm blanks from a strip 178 of stock material. In addition, the die member 174 is provided with a suitably formed aperture 180 which is cooperable with the end of the plunger 160 to form the diaphragm blank into a cup shaped member and direct the formed diaphragm into the end of a primer tube as shown best in Fig. 12.

In order to actuate the die member 170 for cutting a blank and to provide for relative axial movement between this die and plunger 160 to permit the plunger to push the blank through the die 174 and into a primer tube, the plunger 160 has a collar 182 fixed thereto. A compression spring 184 abuts this collar and also abuts an internal shoulder 186 formed on the sleeve 166 so that during the forward stroke of the plunger 160, the sleeve and the die 170 are yieldably urged forwardly by the spring 184. After the die member 170 has cut the blank and is stopped by the die member 174, the spring 184 permits the plunger 160 to continue its forward stroke. Upon reverse movement of the plunger 160, the collar 182 engages the bushing 168 so that the sleeve 166 moves rearwardly with the plunger. In addition, in order to assist in retracting the sleeve 166 and the die member 170, an annular member 188 is slidably disposed within an enlarged counterbore 190 in the body member and is resiliently biased against a shoulder 192 on the sleeve 166 by means of a plurality of springs 194. The springs 194 are preferably retained in position by means of screw members 196 which are threaded into the annular member 188 and are slidable within apertures 198 in member 200.

The strip 178 of stock material, which is preferably paper or the like, is fed from a supply roll 202 disposed on a spindle 204 mounted between stands 206 and 208. The strip is passed downwardly through a suitable guide slot 210 between the body 164 and the plate member 176 of the die structure and is directed by a suitable guide 212 to a feed roller 214 and a cooperating pressure roller 216. The pressure roller 216 is rotatably mounted by means of a shaft 218 between arms 220 and 222 of a bracket member which is pivotally mounted between frames 224 and 226 by a shaft 228. The arm 222 extends upwardly to provide a handle member 230 by which the bracket may be manipulated to swing the pressure roller away from the feed roller during insertion of the paper strip between these rollers. Normally, however, the pressure roller is resiliently urged against the feed roller by means of a spring 232 which is connected between pins 234 and 236 on the handle 230 and frame member 226, respectively.

The feed roller 214 is rotatably supported between the frame members 224 and 226 by means of a shaft 238. In order to drive the feed roller intermittently and during intervals between forward strokes of the plunger 160, a ratchet wheel 240 is connected with the roller 214. A lever member 242 is mounted for pivotal movement about the shaft 238 and carries a spring biased pawl 244 which is engageable with the teeth of the ratchet wheel. The lever member 242 is actuated at intermittent inter-

vals by means of a piston 246 slidably disposed within a single acting air cylinder 248 and connected with the lever member through a rod 250. A suitable spring means, not shown, is provided for retracting the piston 246, and a solenoid valve 252 is provided for controlling the operation of the air cylinder. The valve 252 is connected with a source of air under pressure through an air line 254.

The means 50 for positively positioning a diaphragm to a predetermined depth within a primer tube at the work station 49 is shown in Figs. 3 and 16 through 18. This means includes an elongated rod or plunger 256 having one end slidably supported in a bracket member 258 and its opposite end yieldably connected with a piston 260. The piston is slidably disposed within a double acting air cylinder 262, the operation of which is controlled by a double acting solenoid valve 264. The valve is connected with a source of air under pressure through air lines 266 and 268. The solenoid valve 264 is controlled to limit the forward stroke of the piston by means of a microswitch 270 which is engageable with a cam member 272 adjustably mounted on the rod 256. In addition, a cam member 274 is mounted on the rod 256 and is engageable with a microswitch 276 for a purpose described below. If desired, the rod 256 may be further supported and guided by means of a guide bar or rod 278 and apertured extensions of the cam members 272 and 274 which are slidably received on the guide bar.

In order to insure that the diaphragm will be positively positioned at the desired location within the primer tube, the cam member 272 is located so that the piston and rod 256 may have a stroke in excess of the stroke necessary to insert the diaphragm to the desired depth within the tube. In addition, a pin or lug 280 is mounted on the rod 256 in a position so that it will engage the end of the primer tube 34 as shown in Fig. 18 when the end of the plunger 256 and the diaphragm carried thereby has reached the desired predetermined depth within the tube. Since, as is mentioned above, the cam 272 is positioned so that the stroke of the rod 256 would be too long if it were not for the pin 280, the final location of the diaphragm within the primer tube is always positively determined by the position of the pin 280. It is understood, of course, that by adjusting the positions of the cam member 272 and the pin 280, the diaphragm may be finally located at any desired point between the ends of the primer tube.

In order to prevent injury to the mechanism when the forward stroke of the rod 256 is arrested by engagement between pin 280 with the end of the primer tube, the rod 256 is yieldably connected with the piston 260 by means shown in Fig. 18. This means includes a pipe section 282 fixed on the end of the piston and a sleeve member 284 telescopically associated with the pipe section. A pin 286 extends transversely through the pipe section 282 and through elongated slots 288 and 290 formed in the sleeve member. A compression spring 292 acts between the pin 286 and the closed end of the sleeve member for normally biasing the sleeve member to a fully extended position and for permitting the sleeve member to slide relative to the pipe section when the pin 286 engages the primer tube. As shown in Fig. 18, the rod 256 may be detachably secured to the sleeve member by means of a screw 294 so that rods of various lengths and having pins 280 positioned at various locations may be quickly interchanged.

The means 52 for checking or inspecting the primer tube and diaphragm assembly at the work station 42 is shown in Figs. 3, 19, 20 and 21. This means includes a piston 296 slidably disposed in a double acting air cylinder 298 and controlled by means including a double acting solenoid valve 300. The valve is connected with a source of air under pressure through air lines 302 and 304. A microswitch 306 is fixed on the end of the piston and carries an elongated hollow tube 308 in which is slid-

ably disposed an elongated switch actuating rod 310. The rod 310 is retained for limited movement relative to the tube 308 by snap rings or the like 312 and 314.

When checking the position of a diaphragm within a primer tube, the piston 296 is extended so that the tube 308 and the rod 310 extend into the primer tube as shown in Fig. 21. If the diaphragm is in the proper position, it is engaged by the end of the rod 310 and the rod is moved rearwardly with respect to the tube 308 to actuate element 316 of the microswitch 306 and close the contacts of the switch. This switch functions to operate the solenoid valve 300 so as to retract the piston 296 when the diaphragm is properly positioned. In the event the diaphragm is located too far within the primer tube, the rod 310 will not engage the diaphragm and the microswitch 306 will not be actuated. Thus, the piston will continue to move forwardly until a cam member 318 adjustably mounted on the hollow tube 308 actuates a microswitch 320, which switch operates the solenoid valve to return the piston. The switch 320 also functions to control means described below for separating unsatisfactory primer tube and diaphragm assemblies from satisfactory assemblies. At this point, it is well to note that with the structure of this invention, it is substantially impossible for a diaphragm to be improperly positioned within the primer tube since the diaphragms are positively located by the above described plunger 256. However, it is possible that an operator might inadvertently allow the apparatus of this invention to continue to function after the supply of stock material for the diaphragms has been exhausted so that, of course, the primer tubes would not have any diaphragms inserted therein. The inspecting mechanism just described is therefore most useful in preventing such primer tubes without diaphragms from being accepted.

The inspecting means also includes a microswitch 322 for a purpose which will be described below, which switch is actuated by a cam member 324 mounted on the hollow tube 308. The cam members 318 and 324, like similar cam members described above, are provided with apertured extensions which are slidably on a suitably supported guide rod 326.

The means mentioned above for separating acceptable and unacceptable primer tube and diaphragm assemblies is shown in Figs. 2 and 3 and includes a pair of guide rails 328 and 330 mounted on a rotatable shaft 332. These rails normally project within the circle about which the primer tubes travel while on the conveying disks so that after a primer tube and diaphragm assembly has been found to be satisfactory at the checking station 42, the assembly is stripped from the conveyor disks by the rails and directed to a suitable point of discharge. A lever arm 334 is fixed to the shaft 332 and is also connected with a single acting spring returned piston 336 slidably disposed in an air cylinder 338. The air cylinder is controlled by solenoid valve 340 which is connected with a source of air under pressure by means of a conduit 342. The solenoid valve 340 is, in turn, controlled by the above mentioned microswitch 320 of the inspecting means so that whenever the inspecting means detects an unacceptable primer tube and diaphragm assembly or a primer tube from which the diaphragm is missing, the valve 340 is actuated so that the piston 336 is extended. Upon extension of the piston 336, the shaft 332 is rocked by means of the lever 334 so that the guide rails 328 and 330 are raised. This action allows the unacceptable assembly to continue moving with the conveyor disks past the rails 328 and 330 until it drops from the disks onto a discharge chute 344.

The apparatus of this invention is provided with electrical control means diagrammatically shown in Fig. 22. As will become clear from the description below, this control means functions so that the conveyor is intermittently advanced or indexed to move the primer tubes carried thereby to the various work stations. In addi-

tion, the control means functions to operate the lacquer applying means 44, the diaphragm forming and inserting means 46, the diaphragm positioning means 50, the inspecting means 52 and the reject mechanism in timed relationship with each other and during the intervals between movement of the conveyor.

The control circuit preferably includes a voltage reducing transformer 350 which is connectable with main power lines 352 and 354 by means of a main switch 356. A control box 358 may be mounted at any desired position on or adjacent the apparatus and is provided with a momentary contact push button start switch 360, a momentary contact push button index switch 362 and a similar stop switch 364. One contact 366 of the start switch is connected to the secondary coil of the transformer through wires 368, 370, 372 and 374. The control circuit is also provided with a mechanically latched relay 376 having pairs of cooperating contacts 378-380 and 382-384 which are closed on energization of a solenoid 390 and held closed by a suitable mechanical latch 392. This relay is also provided with a pair of contacts 386 and 388 which are closed on energization of the solenoid 394 and held in the closed position by the latch. The other contact 396 of the start switch is connected with the relay contact 378 through wires 398, 400, 402 and 404. The start switch is also connected to the solenoid 390 of the relay by wire 406 which is connected to the wire 402. The relay contact 380 is connected to a terminal box 408 through wires 410, 412, 414, 416, 418, 420 and 422. The terminal box is also connected with the secondary coil of the transformer through wires 424, 426, 428 and 430. A control mechanism 432 for the conveyor air motor 64 is connected with the terminal box by means of a cable 434. This control mechanism is of commercial and known construction and includes a solenoid valve which may be actuated upon receiving an electrical impulse in the manner described below to start the air motor and microswitch means which is operable after the conveyor has been advanced a predetermined distance to actuate the solenoid valve and stop the air motor.

The electrical circuit is provided with a microswitch 436 which functions to prevent operation of the means 44, 46, 50 and 52 unless a primer tube is properly positioned at the work station 36. Thus, the switch 436 is mounted to be actuated and closed by a primer tube at the work station 36 and one contact of the switch 436 is connected with the wire 402 through wires 438, 440 and 442. The other contact of the switch 436 is connected by wires 444, 446, 448, 450, 452 and 454 with the solenoid valve 300. In addition, the wire 452 is connected with the solenoid valves 264, 154 and 128 by wires 456, 458 and 460, respectively. These solenoid valves are respectively grounded by wires 462, 464, 466 and 468. With the circuit thus far described, it is seen that upon pressing the start button, the relay contacts 378 and 380 will be closed and a momentary electrical impulse will be directed to the solenoid valves 128, 154, 264 and 300, which impulse is sufficient to actuate these valves in a manner which will cause the air pistons controlled by the valves to move forwardly. When the air pistons have reached the forward limits of their respective strokes, a portion of the control circuit, which is to be described, functions to actuate the solenoid valves to return the air pistons and also to start the air motor 64 of the conveyor when all of the pistons have been returned to their retracted positions. After the air motor has indexed the conveyor to predetermined amount, a microswitch, not shown, included in the air motor control mechanism 432 functions to send an electrical impulse through the cable 434, the terminal box 408, and back to the advance side of the solenoid valves 128, 154, 264 and 300 through wires including the wires 422, 420, 416, 414, 412, 410, 404 and 402. It is thus seen that once the start button has been operated, the apparatus will continue to operate in an automatic manner.

In order to return the various air pistons, the above mentioned microswitches 138, 164, 270, 306 and 320 are provided. These switches are connected in parallel with each other and are connected to the secondary coil of the transformer by means including the wire 374 and a wire 470. The microswitch 138 has one contact connected to the wire 470 by a wire 472 and another contact connected to the reverse side of the solenoid valve 128 by means of wires 474, 476, 478 and 480. The switch 164 is connected to the wire 470 by wire 482 and is also connected to the reverse side of the solenoid valve 154 through wires 484 and 486. The switch 270 has one contact connected with the wire 470 by a wire 488 and another contact connected with reverse side of the solenoid valve 264 by wires 490 and 492. The microswitch 306 of the inspecting means has one contact connected with the wire 470 by means of a wire 494 and another contact connected with the reverse side of the solenoid valve 300 through wires 496, 498 and 500. The microswitch 320 has one contact connected to the wire 470 by wire 502 and the other contact connected with the reverse side of the solenoid valve 300 by means of wires 504, 506, 508, 498 and 500. In addition, the microswitch 320 is connected by means of wires 504, 510 and 512 with the solenoid valve 340 so that upon closing of the switch 320, the valve 340 is operated in a manner which will cause the air piston 336 of the reject mechanism to pivot the guide or stripper bars or rails 328 and 330 in the manner described above.

The electrical control circuit includes the above mentioned microswitches 134, 168, 276 and 322 which are connected in series with each other and function to permit indexing of the conveyor only after all of the air pistons of the means 44, 46, 50 and 52 have been fully retracted. More specifically, one contact of the switch 322 is connected with the relay contact 382 through wires 514, 516, 518 and 520. The cooperating relay contact 384 is connected with the secondary coil of the transformer through wires 522, 524, 370, 372 and 374. The other contact of the switch 322 is connected with one contact of the switch 276 through wires 526, 528 and 530 and the other contact of the switch 276 is connected with one contact of the switch 168 through wires 532, 534, 536 and 540. The remaining contact of the switch 168 is connected with one contact of the switch 136 through wires 542, 544, 546, 548, 550 and 552. As shown in Fig. 22, the solenoid valve 252 is connected in series between the wires 544 and 546 so that when all of the switches 134, 168, 276 and 322 are closed, the solenoid valve 252 will be actuated to operate the feeding mechanism for the diaphragm stock material while the conveyor is being indexed. The other contact of the switch 134 is connected with the terminal box through wires 554, 556, 558, 560 and 562. It should be noted that when the air cylinders are in their retracted positions shown in Fig. 22, the actuating members of the microswitches 168, 276 and 322 engage their respective cooperating cams while the actuating member of the switch 134 has been engaged and disengaged by the cam 136. The time required for the stroke of the lacquer applying means 44 is longer than for the strokes of the means 46, 50 and 52 so that when the switch 134 is momentarily closed by the cam 136 during the return stroke of the means 44, the circuit is momentarily established and an impulse is sent to the air motor control mechanism 432, which impulse is sufficient to actuate the control mechanism to start the air motor. It is, thus, seen that the conveyor cannot be indexed until the pistons of all of the means 44, 46, 50 and 52 have been returned to their retracted positions. The switch 134 is a one way switch so that it cannot be closed by the cam 136 during the forward stroke of the air piston of the lacquer applying means 44.

In order to stop the apparatus, the above mentioned stop button 364 is provided. This button is adapted to close a pair of contacts, one of which is connected with

the power line 370 by wire 564. The other contact is connected with the relay solenoid 394 through wires 566, 568, 570 and 572. Thus, upon pressing the stop button, the relay contacts 386 and 388 are closed while the other described contacts of the relay are opened. The stop button is also connected with the advance side of the solenoid valves 128, 154, 264 and 300 so as to insure the return of all the air pistons controlled by these valves when the apparatus is stopped. More specifically, the wire 568 is connected with a wire 569, which wire is connected with wires 480, 486, 492 and 500 through wires 571, 573, 575 and 577, respectively.

There are instances arising when starting or stopping the apparatus when it is desirable to index the conveyor without actuating the various lacquer and diaphragm applying means. To permit such indexing of the conveyor, the index push button 362 is provided. One contact of the index push button switch is connected with the control mechanism 432 of the air motor 64 by wires 574, 576 and 562, the terminal box, and the cable 434. The other contact of the index push button switch is connected with the relay contact 386 by means of wires 578, 580, 582, 584 and 586. The cooperating contact 388 is connected by means of wires 588, 590, 592 to the power line 370 and thus to the secondary coil of the transformer. Thus, to index the conveyor, it is seen that it is necessary to first press the stop button so that the relay contacts 386 and 388 are closed and then to press the index button.

While the operation of the apparatus of this invention is believed to be clear from the above description, a short résumé of the operation is as follows. The operator, of course, first places a supply of primer tubes in the hopper and threads the strip of diaphragm stock material through the die means 162 and the feed mechanism. Then the operator presses the stop button and subsequently presses the index button so that the conveyor is advanced to receive primer tubes from the hopper. Then the operator presses the start button whereupon the lacquer applying means functions to inject lacquer within a limited portion of the primer tube located at the work station 36. It is understood that the apparatus may be adjusted so that the lacquer is applied at any location between the ends of the primer tube. At the same time, the means 46 functions to cut out a diaphragm blank, form the blank and insert the blank into the end of the primer tube located at the station 38. Also simultaneously with the functioning of the lacquer applying means 44 and the die and inserting means 46, the means 50 is actuated to locate a previously inserted diaphragm at any predetermined position between the ends of a primer tube located at the station 40 and the inspecting means 52 functions to check the diaphragm and primer tube assembly at the station 42. When the respective operations of the means 44, 46, 50 and 52 have been completed and the air cylinders of these means have been returned to their retracted positions, the conveyor is automatically indexed in the manner described above and the cycle is repeated.

From the above description, it is seen that the present invention has provided a novel apparatus whereby diaphragms or plug means may be automatically formed and located at a predetermined position within a tubular body such as a primer tube in a rapid and, therefore, economical manner. To emphasize this point, it is noted that the apparatus of this invention with one operator is capable of performing the work heretofore accomplished by twelve operators assembling diaphragms and primer tubes by hand. Furthermore, it is seen that the present invention has provided an apparatus whereby both the lacquer or other adhesive material and the diaphragm are accurately located at a predetermined position within the primer tube so that a minimum of primer tube and diaphragm assemblies will be rejected and more specifically, so that under normal conditions, rejections are substan-

tially eliminated. In addition, it is seen that the present apparatus is fully automatic in operation so that not only are the diaphragms and primer tubes automatically assembled, but also so that operation of the various elements and particularly the lacquer applying means is prevented when the primer tubes are not in proper position. It is also seen that the present invention is constructed so that acceptable primer tube and diaphragm assemblies will be separated from unacceptable assemblies or primer tubes in which no diaphragm has been inserted.

While the preferred embodiment of the present invention has been shown and described herein, it is obvious that many structural details may be changed without departing from the spirit and scope of the appended claims.

The invention is claimed as follows:

1. An apparatus for assembling plug means into tubular bodies comprising intermittently operable means for conveying a series of tubular bodies along a predetermined path of travel with the axes of said tubular bodies extending transversely of said path of travel, intermittently operable means adjacent said path of travel for applying a plug means holding material into a predetermined internal portion of successive tubular bodies on said conveying means, intermittently operable means adjacent said path of travel for successively forming a plurality of plug means from stock material and for positioning the formed plug means into said predetermined internal portions of the tubular bodies on said conveying means, intermittently operable means adjacent said path of travel and spaced from said positioning means along said path of travel for inspecting the interiors of said tubular bodies for proper positioning of said plug means, said inspecting means including a reciprocable tube insertable into the tubular bodies, a tube reversing switch movable with said tube, and a rod slidably disposed in and extending from said tube and engageable with said switch for actuating the switch upon contact with a plug means within a tubular body, additional fixed tube reversing switch means operable by means movable with said tube in the event said rod does not contact a plug means, means for separating properly assembled body and plug means from bodies without a properly assembled plug means, said last mentioned switch means also controlling operation of said separating means, and means for actuating said conveying means, said applying means, said forming and positioning means and said inspecting means in predetermined timed relationship.

2. An apparatus for assembling plug means into tubular bodies comprising means for intermittently conveying a series of tubular bodies along a predetermined path of travel, intermittently operable means adjacent said path of travel for applying a plug means holding material into a predetermined internal portion of successive tubular bodies moving along said path of travel, means for preventing operation of said material applying means unless the tubular body is properly positioned on said conveying

means, intermittently operable means adjacent said path of travel for inserting plug means within successive tubular bodies on said conveying means, means for continuously actuating said conveying means, said material applying means and said positioning means in predetermined timed relationship, and means for initially actuating said conveying means without actuating said plug means inserting means, so that an initial tubular body on said conveying means may be moved into cooperative relationship with said inserting means before actuation of the inserting means.

3. An apparatus for assembling plug members into tubular bodies moving along a path of travel comprising pneumatically reciprocable means adjacent said path of travel for applying plug member holding material into predetermined internal portions of successive tubular bodies moving along said path of travel, pneumatically reciprocable means adjacent said path of travel for successively forming a plurality of plug members from a strip of stock material and inserting successive plug members into successive tubular bodies, pneumatically reciprocable means adjacent said path of travel and spaced from said last named means for positively positioning formed and inserted plug members within said predetermined internal portions of successive tubular bodies, a plurality of electrically operated valves respectively controlling advancing and reverse movement of said first, second and third mentioned means, a plurality of parallel connected switches respectively connected with one of said valves for individually actuating their associated valves for reversing their associated pneumatically reciprocable means, means for indexing the tubular bodies along said path of travel, means including a plurality of series connected switches connecting with said indexing means and respectively actuated by said first, second and third reciprocable means for energizing said indexing means only after all of said reciprocable means have been retracted from said path of travel, and means operable upon completion of each indexing movement of said indexing means for operating said valves to advance said reciprocable means.
